UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 5, 1923, Serial No. 622,909. Renewed May 1, 1925.

To all whom it may concern:

Be it known that I, ALFRED G. F. KUROWSKI, a citizen of the United States, residing in Brooklyn Borough, in the county of 5 King, city and State of New York, have invented certain new and useful Improvements in Typewriting Machines, of which the following is a specification.

The present invention relates to typewriting machines, and more particularly to 10 means for use in connection with the typing or cutting of stencil cards, and is illustrated in connection with features disclosed in my co-pending application, Serial No. 595,235, 15 filed October 18, 1922, and the co-pending application of Alvin E. Zugelter, Serial No. 617,253, filed February 6, 1923.

According to the present embodiment of 20 the invention, the partial rotation of the platen for inserting the stencil card may be effected by means of a finger-piece secured directly to the platen. This finger-piece is secured at one side of the typing zone.

The rotative movement of the platen is 25 limited by means of a stop projecting from one end of the platen frame into a slot formed in a cap on the adjacent end of the platen. To vary the extent of the rotative movement, provision is made of a lever 30 pivoted on the cap to be swung over one end of the slot to bring into position either one of two pin-receiving seats to stop the platen in different positions. Provision is also made of means to stop the lever with 35 either one of the seats in effective position and of means to detain the lever in its limiting positions.

The gaging of the stencil cards may be 40 effected by means of two outwardly projecting members at the ends of a plate which serves to hold one edge of the usual backing on the platen. These projections are in substantial alignment to correspond to the ends of the flange formerly used for such 45 purpose when no ribbon was used back of the stencil card. In the present case the flange is omitted between the end projections to enable a ribbon to be fed around the platen.

To cast off the knurled or toothed rolls 50 which press the edges of the stencil card against the toothed bands or rings on the platen, disclosed in the applications referred to, provision is made of a finger-piece conveniently located adjacent the finger-piece

on the platen, and mounted on a shaft which extends parallel to the platen, and is provided with cams to engage pins on pivoted arms carrying the knurled rolls, the cams being provided with recesses to receive the pins when the knurled rolls are in either effective or cast off positions. Provision is also made of means for adjusting the pressure of the knurled rolls against the toothed bands on the platen.

The means for feeding the ribbon around the platen comprise gears on the ends of ribbon-spool-rotating shafts and displaced relatively to each other longitudinally of the platen, and a gear mounted on a shaft 60 reciprocable longitudinally of the platen to bring the gear thereon into mesh with either one of the gears on the ribbon-spool-rotating shafts. The reciprocable shaft is spring-urged to one of its limiting positions and 65 may be moved in the opposite direction by a resilient lever mounted to swing about a pivot parallel to the shaft. The resilient lever is provided with a cam step to move the shaft longitudinally and its resilient 70 quality permits it to yield when the gear on the reciprocable shaft fails to mesh properly with the gear farthest from the resilient lever.

The invention also relates to improved 75 ribbon-roll structure and to the manner of mounting the feed-rolls.

Other features and advantages will hereinafter appear.

In the accompanying drawings.

Figure 1 is a front elevation showing the invention applied to the platen frame of an Underwood standard typewriting machine.

Figure 2 is a side elevation.

Figure 3 is a sectional side elevation, the section being taken along line 3—3 of Figure 1 and the view being taken in the direction of the arrows.

Figure 4 is a view showing one position of the lever by means of which the limiting 100 position of the platen in one direction is varied.

Figure 5 is a view similar to Figure 4 but showing the lever in a different position.

Figure 6 is a top plan view, partly in section, of the structure shown in Figure 1.

Figure 7 is a view similar to Figure 3 but with a stencil card inserted and the section being taken on the line 7—7 of Fig. 110 ure 6.

Figure 8 is a perspective view of the member which serves to hold the lower edge of the celluloid backing in position, the projections at the ends thereof serving as gages 5 for the lower edge of the stencil card.

Figure 9 is a top view, partly in section, showing the means for regulating the spring pressure of the knurled rolls against the toothed rings on the platen.

10 Figure 10 is a view of the left end of the rear ribbon-roll shown in Figure 6.

Figure 11 is a view showing substantially the same parts as Figure 9, but in separated relation.

15 Figure 12 is a fragmentary view showing one of the knurled rolls in cast-off position.

A cylindrical platen-core 11 of wood, or the like, is mounted on a platen-axle 12 journaled in the ends 13 of a platen-frame 20 comprising a rear paper-table 15, a rod 16 for the usual paper-fingers, not shown, and a rod 17 joining the ends 13 beneath the platen. Brackets 18 fixed on the rod 17 support the usual rock-shaft 18^a by which the usual feed-rolls are cast off. Finger-wheels 19 are provided on the ends of the platen-axle 12, and the platen may also be rotated by line-spacing mechanism, comprising a ratchet-wheel 20, mounted on the platen-axle 12, a pawl 21 pivoted on a slide 22 and a line-space lever 23 by which the slide 22 may be moved rearwardly against the action of a spring 24.

The present invention contemplates the

35 typing or cutting of stencil cards, such as shown at 25 in Figure 7. Such stencil cards usually comprise a center 26 of stencil material and a frame 27 of paper or other suitable material. Inasmuch as the stencil cards 40 25 overlie only a comparatively short central section of the platen, only the necessary central section of the platen-core 11 is covered by an envelope 28 of rubber or the like. Mounted on the platen-core 11, at 45 each side of the envelope 28, are toothed or serrated rings or bands 29 to engage the sides of the frame 27 of a stencil card, the stencil card being held against the rings 29 by means of knurled or toothed rolls 30. 50 To furnish suitable support for the stencil material 26 during typing, provision is made of a backing strip 31 of suitable material, such as celluloid, secured in position by means of upper and lower bars 32 and 33, 55 respectively, overlying the corresponding edges of the backing strip 31 and secured to the platen by suitable means, such as screws 34. The bar 33 is provided at its upper edge with projections 35 to gauge the lower edge of a stencil card 25 to be inserted in the machine. Heretofore, in certain cases, provision has been made of a flange extending along the full length of the member corresponding to bar 33, but, in the present case, the central portion of the flange is

omitted for a purpose to be brought out hereinafter.

Extending across the rear of the platen-frame, and secured to the ends thereof by screws 35^a, is a rod 36 extending through bosses 37 on the rear ends of arms 38, which may be secured at any desired positions along the rod by means of set-screws 38. Said arms 38 are also supported by means of the rod 16, which passes through openings 40 of sufficient size to permit adjustment of the arms relatively to the rod. Such adjustment may be obtained by means of a plate 41 fitting over the rod 16 and secured to the arms 38 by means of screws 42, as more fully disclosed in said co-pending application, Serial No. 595,235. Each arm 38 is provided at its forward end with an inwardly-extending member 43, which, with a resilient member 44, forms a guide for one edge of a stencil-card, the members 43 and 44 being held at a suitable distance apart by means of a spacer 45, the parts 43, 44 and 45 being held in proper relative position by means of screws 46. To assist in guiding the card between the members 43 and 44, the upper ends of these members are flared rearwardly and forwardly, respectively, and the spacer 45 is beveled at its inner edge as indicated in Figure 1. As shown in Figures 1 and 2, each guide-member 44 is provided with a narrow extension 47 which is bent around the shaft 18^a at the bottom of the platen-frame.

Each guide-member 44 is also provided with an opening 48, through which the corresponding roll 30 engages the adjacent toothed band 29, the opening 48 having an upward extension 49 to receive the end of a lever 50, on which the roll 30 is supported by means of a pivot-screw 51. Each lever 50 is pivotally supported by means of a screw 52 passing through the adjacent arm 38 and the depending end of a tongue 53, bent inwardly from the arm 38, and then downwardly parallel thereto, and is urged to press the roll 30 against the band 29, by means of a spring 54 engaging a pin 55 projecting from the lever adjacent the guide-member 44. As shown in Figure 1, the upward extension 49 of the opening 48 is of sufficient width to permit the forward end of the spring 54 and the pin 55 to pass therethrough.

The position of the rolls 30 is determined by means of a finger-piece 56, secured to the left-hand end of a shaft 57, journaled in the arms 38. Adjacent the levers 50, a cam 58 is secured to the shaft 57, by means of a set-screw 59. As shown in Figure 7, each cam 58 engages a laterally-projecting pin 60 at the rear end of the adjacent lever 50, and is provided with an incline 61, such that a rearward swinging of the finger-piece 56 will permit the corresponding roll 30 to be

pressed against the adjacent band 29, but forward movement of the finger-piece 56 will cast off the roll 30. Each cam 58 is also provided, at the ends of the incline 61, 5 with depressions 62, into which the pin 60 may drop and serve to hold the finger-piece in the position to which it has been moved.

According to the present invention, the pressure of each roll 30 on the corresponding band 29 may be adjusted. To this end, 10 the spring 54, at its rear end, is bent around a bushing 63, and its end is inserted in a slot 64, as shown in Figure 11; and the spring is held in position on the bushing 15 by a collar 65, having a hexagonal exterior to permit it to be embraced by a wrench, and a rib 66 extending across the interior thereof, to enter the slot 64, thereby holding the end of a spring in the slot 64 and connecting the collar 65 to the bushing 63 for 20 turning the same. The bushing 63 may be secured to the adjacent arm 38 by means of a screw 67 extending through the bushing 63, the arm 38 and into a nut 68. It will be 25 evident that the tension of the spring may be adjusted by placing a wrench over the collar 65, loosening the screw 67, turning the bushing 63 to the desired position, and then tightening the screw 67.

The rotative movement of the platen may be limited by means of a pin 69 projecting inwardly from the right-hand end 13 of the platen-frame into a slot 70 in a cap 71, secured on the platen-core 11 by means of 30 screws 72 and 73, as shown in Figures 5 and 6. It is desirable, at times, to vary the line on which the typing is begun at the top of the card. To this end, provision is made 35 of a lever 74, pivoted on the cap 71, by means of a screw 75, for swinging movement across the slot 70. The screw 75 is positioned substantially opposite one end of the slot 70, and has a thrust-arm 76 extending across the 40 end of the slot 70 and provided with two pin-receiving seats 77 and 78, respectively, which may be positioned over the slot, as shown in Figures 4 and 5, respectively, the thrust in each case being received directly on the pivot 45 75. As shown in Figure 4, the movement of the lever 74 in one direction is limited by the engagement of the thrust-arm 76 with a bushing 79 projecting from the center of the cap 71, the lever 74 being detained in 50 this position by means of a detent-device 80 on the lever in connection with a depression 81 on the cap. The lever 74 is curved throughout a considerable portion of its length, so as not to extend beyond the 55 periphery of the cap, and then is turned outwardly to provide a suitable support for a handle 82, in a convenient position for operation by the typist. When the lever 74 is shifted to bring the pin-receiving seat 78 over the slot 70, the curved portion of the lever 74 will engage the bushing 79 to

limit the movement of the lever, and the latter will be detained in this position by means of the detent-device 80 engaging in a depression 83 in the cap.

According to the present invention, the partial rotation of the platen-core 11, necessary to insert the stencil-card, may be effected by means of a handle 84, secured to the platen-core 11 by means of screws 85, the handle 84 and the finger-piece 56 being 75 conveniently located with reference to each other, so that the left hand of the typist may be used either to rotate the platen or to cast off the rolls 30.

To make the typing visible, a ribbon 86 80 is fed between the stencil-card and the platen, and the typing impressions are inked thereby and made visible. The ribbon 86 is secured at its ends to a front roll or core 87 and a rear roll or core 88, and may be wound 85 on either roll and unwound from the other. As disclosed in Figures 6 and 10, the ribbon is attached to the rear roll 88 by means of a retainer 89, having a straight portion 90 to press the ribbon into a groove 91 in 90 the roll, and spring-arms 92 to permit the straight portion 90 to be lifted out of the groove preparatory to placing the end of the ribbon over the groove and returning the retainer to effective position. The roll 88 95 is also provided with a slot 93 for connection with a suitable driving means.

The ribbon-winding mechanism is supported principally by two plates 94, having 100 slots 95 and 96, to fit down over the rods 36 and 16, respectively, each of the plates 94 being held in position on said rods 36 and 16 by means of a screw 97 threaded through a block 98 and engaging the lower part of the rod 36, as shown in Figure 3. Each block 98 may be secured to the corresponding plate 94 by means of screws 99. Fixed at their outer ends in the plates 94 are left-hand sleeves 100 and right-hand sleeves 101. 105 Passing through each of the left-hand sleeves 100 is a driving shaft 102, having at its right-hand end a spool-head 103 provided with an extension 104 to enter the slot 93 of the adjacent roll. At the left-hand ends, the forward and rearward shafts 102 are 110 provided with gears 105 and 106, respectively, offset with respect to each other, as shown in Figure 6.

Passing through each of the sleeves 101 is a shaft 107, carrying a spool-head 108 120 passing through the corresponding ribbon roll or core. Each of the shafts 107 is provided with a reduced end 109, which fits into a recess 110 in the end of the corresponding shaft 102, and with a knurled head 111 to facilitate its insertion and removal, and with a groove 112 just inside of the knurled head to receive a latching lever 113, pivoted at 114 on the right-hand plate 94. It will be 125 evident that, when the levers 113 are in their 130

normal positions, the shafts 107 will be held against longitudinal movement, and that, when the upper ends of the levers 113 are swung rearwardly to bring the lower ends of the levers in contact with stop-pins 114^a, the levers 113 will be retained in such positions by means of detent-projections 115 thereon engaging recesses 116 in the right-hand plate 94. The shaft 107 may then be removed or inserted without interference.

The ribbon-rolls 87 and 88 may be driven by means of the line-space lever 23, and the slide 22 in the usual manner, motion being transmitted from the slide 22 by means of a link 117 to an operating arm 118, loosely mounted on a shaft 119, journaled at its right-hand end in the left-hand plate 94 and at its left-hand end in a bracket 120, secured to the top of the left-hand end 13 of the platen-frame by means of screws 121. Mounted on the shaft 119, adjacent the operating arm 118, is a broad ratchet-wheel 122, to be actuated by a pawl 123, mounted on a pivot 124 on the operating arm 118, and urged into engagement with the ratchet-wheel 122 by means of a spring 125. Retrograde action of the ratchet-wheel 122 is prevented by a pawl 126, mounted on a pivot 127 on the bracket 120, and urged against the ratchet-wheel 122 by means of a spring 128.

Fixed on the shaft 119, near its right-hand end, is a gear 129 normally in mesh with the gear 106, due to the action of a spring 130^a interposed between the right-hand face of the gear 129 and the left-hand plate 94. When the gear 129 is in this position, actuation of the line-space lever will cause the ribbon 86 to be wound on the rear core 88 and unwound from the front core. When it is desired to reverse the direction of feed of the ribbon, the shaft 119 is shifted to the right sufficiently to bring the gear 129 thereon into engagement with the gear 105. It should be understood that the breadth of ratchet-wheel 122 is sufficient to maintain the connection with the pawl 123, irrespective of such shifting of the shaft 119.

As herein disclosed, the shifting of the shaft 119 is effected by means of a resilient lever 130, pivoted on the bracket 120 by means of a screw 131. The lever 130 is provided at its upper end with a knob 132 for engagement by the fingers, and is provided at its lower end with a cam-step, as illustrated in Figures 1 and 2. When the knob 132 is pulled forwardly, to bring the lower part of the lever 130 against a pin 133 on the bracket 120, the shaft 119 will be in its left-hand position, as indicated in Figure 1. When, however, the knob 132 is shifted rearwardly, the shaft 119 will be cammed to the right sufficiently to bring the gear 129 into mesh with the gear 105. Operation of the line-space lever 23 will then rotate the for-

ward ribbon-core 87 and reverse the previous direction of feed.

When one of the shafts 102 is released from the driving shaft 119, and the other shaft 102 is driven, the released shaft may overrun. To avoid such overrunning, provision may be made of suitable retarding means, such as a friction-spring 134, as shown in connection with the gear 106 in Figure 6.

In practice, the typing of a stencil-card 25 may be effected substantially as follows. The rolls 30 are cast off by means of the finger-piece 56, and the stencil-card is inserted downwardly through the guides and gaged by the projections 35, as indicated in Figure 3. The finger-piece 56 is then swung rearwardly to render the rolls 30 effective, and the handle 84 is swung forwardly to feed the stencil-card to the position shown in Figure 7, preparatory to typing on the upper line of the card. It will be seen that the finger-piece 56 and the handle 84 are so located that they may be conveniently actuated in succession by the left hand of the typist. Line-spacing of the card 25 may be effected by the line-space lever 23. The lever 74 for determining the extent of the inserting movement of the platen-core is usually set as shown in Figure 4, but, when it is desired to type at a higher position on the card, the lever 74 is thrown to the position shown in Figure 5.

Upon completion of the typing, the card 25 may be grasped by the typist and drawn out of the machine, the platen being restored in this manner to its initial position for the insertion of another card. The rolls 30 may then be cast off preparatory to the insertion of another card.

Variations may be resorted to within the scope of the invention, and portions of the improvements may be used without others.

Having thus described my invention, I claim:

1. In a typewriting machine, the combination with a cylindrical platen having thereon feeding rings so spaced as to engage the edges of a card, of a handle secured to the platen at one side of the card-feeding rings.

2. In a typewriting machine, the combination with a cylindrical platen, of a handle secured to the platen intermediate its ends for effecting partial rotation of the platen, and means for limiting the rotative movement of the platen, comprising a finger-piece on one end of the platen shiftable to different positions to vary the extent of movement of the platen.

3. In a machine for typing stencil-cards, in combination, a cylindrical platen, a backing strip over which a stencil-card is positioned during typing, and a plate with upstanding projections at its ends secured to the platen to hold the lower edge of the

backing strip against the platen, the up-standing projections serving to gage the lower edge of the stencil-card to be inserted and being spaced apart sufficiently to permit an inking ribbon to be fed around the platen back of the stencil-card.

4. In a typewriting machine, a revolute platen having in one end an arcuate slot concentric with the platen axis, a fixed stop 10 projecting into said slot, and a member mounted on the end of the platen for movement across the slot to vary the effective length thereof.

5. In a typewriting machine, a revolute platen having in one end an arcuate slot concentric with the platen axis, a fixed stop 15 projecting into said slot, a member mounted on the end of the platen for movement across the slot to vary the effective length thereof, and means to detain said member in any position to which it may be set.

6. In a typewriting machine, a revolute platen having in one end an arcuate slot concentric with the platen axis, a fixed stop 20 projecting into said slot, a member mounted on the end of the platen for movement across the slot to vary the effective length thereof, means to detain said member in any position to which it may be set, and means to 25 check said member in the limiting positions to which it may be set.

7. In a typewriting machine, a revolute platen having in one end an arcuate slot concentric with the platen axis, a stationary 30 pin projecting into said slot to limit the movement of the platen, and means to vary the length of the slot, comprising a lever pivoted at a point substantially in a prolongation of the slot and having an arm 35 to be engaged by the pin, the pressure of the pin acting substantially longitudinally of said arm and against the pivot.

8. In a typewriting machine, a revolute platen having in one end an arcuate slot 40 concentric with the platen axis, a stationary pin projecting into said slot to limit the movement of the platen, and means to vary the length of the slot, comprising a lever pivoted at a point substantially in a prolongation of the slot and having a thrust 45 arm having two pin-receiving seats in its ends at different distances from the pivot.

9. In a typewriting machine for typing address stencil-cards, in combination, a 50 platen having spaced stencil-feeding rings for feeding a stencil-card tangentially to the platen without bending it, spring-urged feed-rolls co-operating with said rings to feed the stencil-cards, means controlling the feed-rolls to make them effective when a card has been inserted between the feed-rolls and the platen, and a crank-handle 55 attached to the platen at one side of said rings in proximity to the feed-roll-controlling means for quickly feeding the inserted sten-

cil-card down a short distance to first writing-line position immediately after the feed-rolls have been made effective.

10. In a typewriting machine for typing address stencil-cards, in combination, a 60 platen, means for guiding the stencil-cards tangentially across the face of the platen, stencil-card-gaging means on the platen, means for limiting advance of the platen to locate the stencil-card-gaging means in 65 position to intercept an inserted stencil-card, feed-rolls co-operating with the platen to feed the stencil-card, and a crank-handle fast to the platen for quickly rotating the platen to feed the stencil-card down a short 70 distance to first writing-line position.

11. In combination, a cylindrical platen, a feed-roll to run thereon, a pivoted arm to support said feed-roll, a spring having one end in engagement with the arm to 75 press the feed-roll against the platen, and a rotatable adjusting device comprising a rotatable bushing having across one end a straight slot to receive the corresponding end of the spring, and a collar to fit over 80 the bushing and having a web extending across the opening to fit into the slot when the collar is placed over the bushing.

12. In combination, a cylindrical platen, a feed-roll to run thereon, a pivoted arm to 85 support said feed-roll, a spring having one end in engagement with the arm to press the feed-roll against the platen, and a rotatable adjusting device comprising a rotatable bushing having across one end a straight slot to receive the corresponding 90 end of the spring, and a collar to fit over the bushing and having a web extending across the opening to fit into the slot when the collar is placed over the bushing, and a 95 periphery suitably shaped for effective engagement by a wrench.

13. In a typewriting machine, a platen, line-spacing mechanism for the platen, and means for feeding a ribbon around the platen comprising two parallel shafts for winding opposite ends of the ribbon, gears on said shafts displaced relatively to each other longitudinally of said shafts, and a longitudinally reciprocable shaft having 100 fixed thereon a gear to mesh with either of the gears on the ribbon-winding shafts and a ratchet-wheel actuatable by the line-spacing mechanism.

14. In a typewriting machine, a platen, line-spacing mechanism for the platen, means for feeding a ribbon around the platen comprising two parallel shafts for winding opposite ends of the ribbon, gears on said shafts displaced relatively to each other longitudinally of said shafts, and a reciprocable shaft having fixed thereon a gear 115 to mesh with either of the gears on the ribbon-winding shafts and a ratchet-wheel 120 actuatable by the line-spacing mechanism, and 125

- means including a resilient cam-lever swingable across the end of the reciprocable shaft to shift it for reversing the feed of the ribbon.
15. In a typewriting machine, a platen, line-spacing mechanism for the platen, means for feeding a ribbon around the platen comprising two parallel shafts for winding opposite ends of the ribbon, gears on said shafts displaced relatively to each other longitudinally of said shafts, and a reciprocable shaft having fixed thereon a gear to mesh with either of the gears on the ribbon-winding shafts and a ratchet-wheel actuatable by the line-spacing mechanism, and means including a resilient cam-lever swingable across the end of the reciprocable shaft to shift it for reversing the feed of the ribbon, and yieldable in case of failure of the gear on the reciprocable shaft to mesh with the gear toward which it is urged by said lever.
16. In a typewriting machine, a platen, a platen-frame, two rods extending from side to side of the platen-frame, two plates slotted to rest on said rods, means to secure the plates against movement along the rods, sleeves extending inwardly from the two plates in alignment with each other, a shaft in one of said sleeves held against longitudinal movement and having a central recess in its inner end, a shaft longitudinally slidable in the opposite sleeve and having a reduced end to enter said recess and a slot adjacent the corresponding plate, and a lever pivoted on the last-mentioned plate to enter the slot in the longitudinally slidable shaft and hold it against longitudinal movement.
17. In a typewriting machine, a revoluble platen, a platen-frame, arms supported at the rear of the platen and extending to the front thereof, card-edge guides at the forward ends of said arms, feed-rolls to press against the platen adjacent said guides, levers pivoted on said arms and having the feed-rolls pivoted on their forward ends and laterally-extending pins at their rear ends, a guide-shaft extending across the platen-frame above the rear ends of said levers, and pin-engaging cams on said shaft and comprising inclines to shift the pins to cast-off or restore the rolls, and recesses at the ends of the inclines to receive the pins to detain the cams in their limiting positions.
18. In a typewriting machine, the combination with a platen for a stencil-card, of a gage on the platen in the path of the stencil-card, the gage being rotatable with the platen, and the stencil-card being stiff and therefore feedable tangentially with reference to the platen, a handle fast to the platen to feed the stencil-card down to writing position, and means to arrest the stencil-card after the gage has left contact with the stencil-card to locate the card in writing position.
19. In a typewriting machine, the combination of a rotatable platen, line-spacing mechanism to rotate said platen to feed a work-piece past the printing point of the platen, stop means for limiting the line-space movement of the platen by said mechanism, a finger-piece permanently secured to the platen to rotate the platen in a reverse line-space direction to feed the work-piece into the machine, and stops means for limiting the reverse movement of the platen.
20. In a typewriting machine, the combination of a revoluble platen movable with a forward line-feeding movement in the typing operation, and also in a reverse direction to feed a piece of work to typing position, a finger-piece pivoted on the end of the platen, a carriage for the platen having a stop located in the path traversed by the finger-piece during the rotation of the platen in the aforesaid reverse direction, said finger-piece being movable to dispose different portions thereof for engagement with the stop, for stopping the platen in different rotative positions, and correspondingly determining the line of typing on the piece of work, and means for limiting the movement of the finger-piece in either of two directions to thus determine the portion of the finger-piece which will be disposed for engagement with the stop.
21. In a typewriting machine, the combination of a revoluble platen, a platen-frame to support said platen, two co-operative stop-elements to limit the rotation of the platen, one of said stop-elements being carried by the platen, and the other stop-element being carried by the platen-frame, one of said stop-elements having a plurality of stops arranged in stepped relation thereon and being pivotally supported, and a finger-piece to set the pivoted stop-element to bring any one of its stops into effective relation with the co-operative stop-element to vary the rotation of the platen.
22. In a typewriting machine, the combination of a platen having a gage thereon for a stencil-card, means for line-feeding the platen forwardly, means for stopping the forward movement of the platen at a point where the gage is in a position to be engaged by a stencil-card as it is fed to the machine, a finger-piece secured to the platen for moving it in the reverse direction, means for guiding the stencil-card downwardly in front of the platen during the reverse movement of the platen, and means for stopping the reverse movement of the platen at a point where the stencil-card is properly positioned to receive the first line of typing.
23. In a typewriting machine, the combination of a revoluble platen, means on the platen for gaging a piece of work as it is

fed to the machine, a finger-piece mounted on the end of the platen for movement into different positions relative to the platen, a carriage having a stop thereon located in the path traversed by the finger-piece in the rotation of the platen, and means for limiting the movement of the finger-piece in

either of two directions, said finger-piece when at its limits of movement having pre-determined relations to the gaging means 10 for determining the positions at which the piece of work receives the first line of typing.
